UNITED STATES PATENT OFFICE.

GERMAINE BEAUDREAU MCKENZIE, OF TREDINOCK, PENNSYLVANIA.

DESIGN FOR A BADGE OR SIMILAR ORNAMENT.

47,647.

Specification for Design.

Patented July 27, 1915.

Application filed April 1, 1915. Serial No. 18,619. Term of patent 14 years.

To all whom it may concern:

Be it known that I, GERMAINE BEAUDREAU MCKENZIE, a British subject, residing at Tredinock, Elkins Park, Montgomery county, Pennsylvania, have invented a new, original, and ornamental Design for a Badge or Similar Ornament, of which the following is a specification, reference being had to the accompanying drawing, forming part thereof.

The figure is a plan view of a badge or similar ornament showing my new design which comprises a Maltese cross having in its center an emblazoned shield.

I claim:

The ornamental design for a badge or similar ornament substantially as shown and described.

GERMAINE BEAUDREAU MCKENZIE.
